UNITED STATES PATENT OFFICE.

EDWARD J. PENNINGTON, OF NEW YORK, N. Y.

IGNITION-PLUG FOR HYDROCARBON-MOTORS OR EXPLOSION-ENGINES.

No. 870,902.

Specification of Letters Patent.

Patented Nov. 12, 1907.

Application filed August 7, 1907. Serial No. 387,390.

To all whom it may concern:

Be it known that I, EDWARD J. PENNINGTON, a citizen of the United States, residing at New York, in the borough of Manhattan and State of New York; have invented new and useful Improvements in Ignition-Plugs for Hydrocarbon-Motors or Explosion-Engines, of which the following is a specification.

This invention is more particularly intended for use with engines employing medium or poor quality of gasolene or coal oil, kerosene or alcohol, although it is equally well adapted for use with gas or other types of explosion engines.

In carrying out my invention, I employ for the insulation of the positive from the negative element such substances as porcelain, mica or the like, such use forming no part of my invention, which consists in novel constructions and combinations of parts herein-after described, and which are productive of useful or improved results as pointed out.

20 In the accompanying drawing Figure 1 is an elevation embodying features entering into my invention. Fig. 2 is a longitudinal sectional view of Fig. 1. Fig. 3 is an end view of Fig. 2 modified as hereinafter mentioned. Fig. 4 is a fragmentary longitudinal section also showing the modification seen in Fig. 2. Fig. 5 is an enlarged view of a part of the positive element in its preferred form. Fig. 6 is an enlarged vertical sectional view of a preferred form of the negative element.

Fig. 7 is an end view, partly in section, showing the 30 relations of the positive and negative elements illustrated in Figs. 5 and 6. Fig. 8 is a longitudinal sectional view of a modification. Fig. 9 is an end view partly in section of Fig. 8.

In the form of my invention seen in Figs. 1 and 2, 35 1 represents a porcelain insulating body, which is inclosed or embraced by the main casting or frame 2, the latter being adapted to be screwed into the engine or cylinder. The casting may be chased with two or more threads as shown; thus one may be a metric, another a U. S. standard, and a third a large metric, or otherwise. A nut 3 is provided with an annular neck which slips over the porcelain insulating body 1, the neck having a thread 3^a which engages a threaded part of the casting 2, the nut 3 fitting against a shoulder 3^b 40 of the insulating body 1, and serving to force it tightly against a packing 4 interposed between a second shoulder 3^c upon said body and another shoulder formed within the main casting 2. By such means the insulating body 1 is effectively yet adjustably held within 50 the said casting.

The insulating body 1 is furnished with a longitudinal bore into which is fitted the positive element 5, the inner and outer ends of which are threaded as shown and for purposes to be described. The outer end is

furnished with a nut 6 to which the terminal wire is 55 attached and the inner end with a nut 7, a washer 8 being interposed between the nut and the inner end of the porcelain material 1 as shown.

9 represents the negative element which is confined within the cylindrical inner portion of the frame or 60 casting 2; a gap 10 existing between the positive element 5 and the inner annular surface of the negative element 9. A baffle plate 11, see Fig. 2, is so arranged that the inner end of the plug may be wholly covered thereby, said plate being imperforate or unfurnished with holes for the egress of the gases, the explosion taking place inside of the combustion chamber and the flames shooting through holes 12^a drilled in its walls. This construction is shown in Figs. 1 and 2, the combustion chamber being indicated by 12. 70 In Figs. 3 and 4 the baffle plate is in fact the negative element indicated by 9^a which is provided with holes leading horizontally into the cylinder.

One of the main features of my invention, and one which gives great efficiency to this improved igniter, 75 is the employment of a positive and a negative element each of which is oppositely threaded or equivalently formed, the positive element having, say, a right hand thread and being arranged concentrically of the annular negative element which may have, say, a left 80 hand thread; or the arrangement may be vice versa. Such construction allows a current or spark to jump endwise or at a right angle to the reversely threaded positive and negative elements, respectively, and also allows two or more sparks to pass from the positive to the negative, or the negative to the positive element simultaneously. The efficiency and certainty of action are thereby greatly increased.

Under one form of my invention, as seen in Figs. 1 and 2, the combustion chamber 12 is closed by a solid 90 baffle plate 11 and the walls of the combustion chamber are radially perforated as shown by 12^a the explosion taking place in the combustion chamber, and the flames being shot through the holes 12^a into the cylinder. Under the other form of my invention, as 95 seen more particularly in Fig. 4, the negative element 9^a is perforated as indicated at 12^b, and the walls of the combustion chamber are solid. Under each construction the effect is the same.

In Figs. 8 and 9 a modification is presented in 100 which the positive element 5 is longitudinally bored and a spring valved rod 5^a placed concentrically to said element, the valved inner end of the rod being closed upon its seat through the medium of the outer spring 5^b confined between a wall of the positive element and a nut 5^c upon the outer end of the said rod. 105

In Fig. 2 practically two combustion chambers are found, one on each side of the negative element 9;

and my invention includes a construction in which one or more of such chambers may be thus employed.

Having thus described my invention, I claim:—

5. 1. In an electric ignition plug, the combination of a positive and negative element each provided with threads, those on the positive element being right and those on the negative left handed, or *vice versa*, substantially as set forth.
10. 2. In an electric ignition plug, the combination of positive and negative elements concentrically arranged as described, each provided with threads, those on the positive being right and those on the negative left handed, or *vice versa*, substantially as set forth.
15. 3. An electric ignition plug having a combustion chamber, combined with reversely threaded positive and negative elements concentrically arranged as described, said combustion chamber having inlets and outlets of aggregate area less than that of the chamber itself, substantially as set forth.
20. 4. An electric ignition plug having a series of combustion chambers provided with holes for the egress of gases and exploded mixture having an area aggregating less than that of the combustion chambers, combined with reversely threaded positive and negative elements concentrically arranged, substantially as set forth.
25. 5. In an electric ignition plug having a series of combustion chambers, reversely threaded positive and negative elements, said combustion chambers having holes for the egress of gases and exploded mixture of an area aggregating less than that of said combustion chambers, 30 substantially as set forth.
6. In an electric ignition plug, a main casting or frame, an insulating body forming a combustion chamber between said casting and body, and reversely threaded positive and negative elements concentrically arranged, a 35 gap being formed between the said elements, substantially as set forth.
7. In an electric ignition plug, a main casting or frame adapted to be screwed into the cylinder, an insulating body forming a combustion chamber between said casting and body, reversely threaded positive and negative elements concentrically arranged so as to form a gap between the said elements, and baffle plate inclosing the end of said casting, the said combustion chamber being provided with openings leading to the cylinder, substantially as 40 set forth.

In testimony whereof I affix my signature in presence of two witnesses.

EDWARD J. PENNINGTON.
